FREDERICK W. COLE, OF NEWTON HIGHLANDS, MASSACHUSETTS, ASSIGNOR TO GAMEWELL FIRE ALARM TELEGRAPH COMPANY, OF NEW YORK, N. Y., A CORPORATION OF NEW YORK.

ELECTRIC SWITCH.

1,294,053.

Specification of Letters Patent. Patented Feb. 11, 1919.

Application filed January 3, 1916. Serial No. 69,783.

To all whom it may concern:

Be it known that I, FREDERICK W. COLE, a citizen of the United States, residing at Newton Highlands, in the county of Middlesex and State of Massachusetts, have invented an Improvement in Electric Switches, of which the following is a specification.

The invention is directed to an electric switch which, while capable of general use, is particularly well adapted for use as a shunt switch for fire-alarm signal boxes.

In switches of the spring type, with which the present invention is more particularly concerned, it is of importance, in view of the comparatively limited movement of the circuit closing members, that the maximum contact area be obtained upon the initial engagement of the terminals; and that from such initial contact to the finally arranged position of such terminals there be an increased pressure between the terminals to insure efficiency and consequently it is the object of this invention to provide a switch fulfilling the above-named requirements.

25 In the drawings:—

Figure 1 is a side elevation of the electric switch embodying this invention, the switch elements being shown in closed relation.

Fig. 2 is a similar view with the switch members in open relation.

Fig. 3 is a fragmentary detail, illustrating the engagement of the switch elements.

Fig. 4 is a side elevation of a modified form of switch embodying this invention.

35 Fig. 5 is an enlarged fragmentary detail, illustrating in full and dotted lines, the relative movements of the switch elements.

In the form illustrated in Figs. 1 to 3, 10 represents the base to which the switch-members are, or may be, secured. One such member, hereinafter referred to as the stationary member, is here shown as comprising a resilient supporting strip of metal bent to form an attaching-portion 12, a lateral body-portion 13, approximately at right angles to the attaching-portion 12, and a switch terminal or engaging portion 14, the latter being bent at an acute angle to the plane of the body-portion 13. The other 45 switch member, hereinafter termed the movable switch member, is shown as consisting of a resilient supporting strip of metal bent to form an attaching-portion 16, adapted to be secured to a base, a body-portion 17, and 55 a terminal or engaging-portion 18, the latter

being disposed at an obtuse angle to the body-portion 17. The movable switch-member is formed intermediate the body-portion and attaching-portion in a full curve 21, so that the body-portion and attaching-portion are approximately parallel, under normal conditions, and at appreciably spaced relation. This return bend 21 constitutes the main point for permitting necessary movement of the switch element 18. A 60 return bend 20 between the body-portion 13 and switch-terminal 14 of the stationary switch member, and of approximately an acute angle, though slightly rounded, constitutes the main point of movement of the 65 switch terminal of the stationary member. The respective switch-members are secured on the base so that in the normal position of the parts, that is, when the switch is open, the respective switch terminals 14 and 18 70 are disposed in superimposed relation, at an angle to both body-portions 13 and 17 of the members and in spaced parallel relation. It is to be noted particularly that the respective terminals 14 and 18 are connected to 75 their supporting strips or body-portions at relatively opposite ends, that is, as here shown, the terminal 14 is connected at its relatively lower end to its body-portion, and the terminal 18 is connected at its relatively 80 upper end to its body-portion, said terminals being thus oppositely disposed. Furthermore, it is to be particularly noted that the switch-members are relatively disposed so that the outer sides of the angles of their 85 angularly formed ends engage each other, as contrasted with the inner sides.

Movement is imparted to the movable switch-member by a plunger, here shown as comprising a head or end-portion 30, and a 90 stem 31, the latter extending through aligned holes in the body-portion 17, and attaching-portion 16 of the movable member, and through a hole in the base. The plunger is adapted to be moved in a straight line, that 95 is, at right angles to the plane of the body-portion 17 of the movable member, the movement being imparted to the plunger, in the signal-box use of the switch through the closing of the signal-box door. It will be 100 further noted from Fig. 1 of the drawings, that the opening for the plunger in the body-portion 17 of the movable switch-element is of increased diameter as compared with the stem of the plunger, permitting a 105 110

relatively free movement of the body-portion 17 under switch action, for a purpose which will later appear. When pressure is applied to the plunger, the body-portion 17 of the movable switch-element, together with the terminal 18 carried by it is moved toward the stationary element, this movement utilizing the return bend 21 as what may be termed a pivotal support. The relative disposition of the terminals 14 and 18 is such that in the continued movement of the plunger, these terminals engage, and engage throughout their maximum area upon the initial contact. The further movement of the plunger causes the terminal 18 to slide to a slight degree upon the terminal 14, resulting in a wiping action to increase the certainty of maximum conductivity. During such wiping action it will be obvious that the relative positions of the terminals change, and that this comparatively slight change in relative positions is compensated for through the fact that the free end of the terminal 14 is opposite the connected end of the terminal 18, and vice versa, so that the effect is to still maintain the full maximum area of contact. During this sliding movement it will be noted that as the terminal 18 is moving in approximately a line parallel to the line of switch closing pressure, and is meeting a terminal disposed at an angle to such line of pressure, that is, the terminal 14, hence there is of necessity an increased pressure incident to and during such advance of the terminal 18, said terminal 18 acting as a wedge or in a wedge-like manner against the terminal 14. As before stated, the terminal 18, by reason of its comparatively remote yielding point, namely, the bend 21, is somewhat more flexible than the terminal 14, owing to its comparatively close yielding point, namely, the bend 20. It, therefore, follows that the terminal 18 yields to a somewhat greater extent than the terminal 14, and that as the yielding point of such terminal 18 is in the form of a return bend, and comparatively remote, such yielding will be in the nature of a spring resistance, which spring resistance increases as the necessity for such yielding increases, so that the further the movement of the element 18 toward closing position, the greater the strength of the spring bend 21 to resist relatively upward movement of said element, and hence the greater pressure of contact between the switch terminals.

One of the circuit wires may be connected with a screw 35, which is, or may be applied, 60 as one of the attaching screws for the movable member, and the other circuit wire connected to a binding post 40, the threaded end of which extends through the base and serves as an attaching screw for the stationary member. To facilitate the connec-

tion of the circuit wires to the binding-post, the upper end-portion of the latter may be beveled, and the binding screw extended therethrough in diagonal relation with the box.

In the embodiment of the invention shown in Fig. 4, each switch-member comprises a body portion 50, which also serves as an attaching portion, and an engaging-portion or terminal 51, the engaging-portions being arranged obliquely to the body-portions, in this instance being arranged at obtuse angles with relation thereto. The engaging-portions or terminals are disposed in parallel relation and relatively oppositely disposed, and the angularly formed switch-members are arranged for engagement at the outer sides of their angles, and hence have substantially the same co-action to that described in connection with the form shown in Fig. 1. In this instance, however, the wedging action is secured through the comparatively equal yielding of both members, each forming a yielding abutment to resist movement of the other.

I claim:—

1. In an electric switch, a stationary switch member and a movable switch member, each switch member formed of a resilient strip having an attaching portion for attachment to a base, a resilient body portion extending from the attaching portion, and a reflexed flat contact portion at the end of said body portion, each stationary switch member being resilient as a whole from the attaching portion to the extremity of the strip and each contact portion thereof being independently resilient from its junction with the body portion to its end, said switch members being oppositely arranged with their contact portions at other than a right angle to the line of switch closing motion whereby the contact portions engage with a wedging action and, in the open condition of the switch, are spaced apart substantially parallel to each other, the above described construction of the switch members being such that, in the closing movement of the switch, said contact portions are moved into substantially simultaneous contact over their entire contacting faces and, with a continued switch closing movement, said contact portions maintain their substantially full contacting area with a sliding engagement therebetween, the independent resiliency of the contact portions maintaining contact therebetween over substantially the entire contact area and the resiliency of each member as a whole permitting the sliding of the contact surfaces while in full area of contact.

2. In an electric switch, a base, a stationary switch member, comprising a resilient strip having a reflexed portion attached to said base, an upright portion extended above

- 5 said base, and a reflexed portion downwardly extended toward said base at the end of said upright portion to form the contact portion of said switch member; a movable switch member formed of a resilient strip having an attaching portion secured to said base, and reflexed to provide a resilient arm extended toward the contact portion of the stationary switch member and having an upwardly extended end forming the contact portion of said movable switch member, which contact portion is arranged to be substantially parallel with the contact portion of the stationary switch member in the open circuit condition of the switch, said movable switch by its resiliency tending to normally remain in open circuit position, an operating member therefor including a rod slidably arranged in said base 10 and extended through said resilient arm and in normal engagement therewith said rod having an abutment adapted to engage with said base to restrict the open circuit movement of said movable switch member, a movement of said operating member toward said base serving to move the contact portion of said movable switch member into substantially simultaneous parallel engagement with the contact portion of said stationary switch member and, upon continued movement of said movable switch 15 20 25 30 member, to continue to maintain said substantially parallel engagement with the contact portion of said stationary switch member, and said movable switch member through its resiliency serving to return itself and said operating member to normal open circuit position upon release from closed circuit position.
3. In an electric switch, two resilient strips, each bent to form an attaching portion, a body portion, and a terminal, said terminals being arranged at an angle other than a right angle to the line of switch closing motion thereby to co-engage with a wedging action, and being deflectable whereby they may engage throughout their full contact area upon initial contact, and continue such area for contact as the closing motion continues, and a sliding plunger extended through the wall in one of said body- 40 45 50 portions and adapted to be moved longitudinally to move said body-portion to cause its terminal to engage the other terminal.
- In testimony whereof, I have signed my name to this specification in the presence of two subscribing witnessses.

FREDERICK W. COLE.
